UNITED STATES PATENT OFFICE.

CHARLES JEWETT SAXE, OF MONTREAL, QUEBEC, CANADA.

ADJUSTABLE STOP FOR WINDOWS OR DOORS.

1,225,862.

Specification of Letters Patent.

Patented May 15, 1917.

Application filed December 13, 1915, Serial No. 66,617.

To all whom it may concern:

Be it known that I, CHARLES JEWETT SAXE, a citizen of the United States of America, and resident of the city of Montreal, Province of Quebec, Canada, have invented certain new and useful Improvements in Adjustable Stops for Windows or Doors, and do hereby declare that the following is a full, clear, and exact description 10 of same.

This invention relates to an adjustable device for holding swinging windows or doors in a desired position such as ajar and it has for an object to economize space in the 15 application of the device to the window or door, to avoid unsightliness and minimize exposure of such device to the elements.

The above with further objects and advantages will be hereinafter more fully described and particularly pointed out in the appended claims.

For full comprehension, however, of my invention reference should be had to the accompanying drawings forming a part of 25 this specification, in which similar reference characters indicate the same parts and wherein:

Figure 1 illustrates partly in elevation and partly in vertical section the lower 30 hinged corner of a window, adjacent frame and my improved stop;

Fig. 2 is a horizontal section on line 2—2

Fig. 1, with the window closed;

Fig. 3 is a transverse section on line 3—3

35 Fig. 2; and

Fig. 4 is a view similar to Fig. 2, with the window ajar.

This adjusting device is equally well adapted for use in connection with a hinged 40 door, window or other swinging member but I have illustrated same as applied to a window and referring now to the drawings, 2 indicates the window which is hinged at 3 to the frame 4 or other stationary part.

45 Set either in the frame or other stationary member 4 or in the sash is a device which, when the window is swung to a desired position is automatically adjusted to hold the window in such position and act as a stop

50 to prevent accidental swinging. In the preferred form the device consists of a friction drag attached to the edge of the frame to which the window is hinged and located in a preferably round recess 5 formed in

the edge of the hinged side of the window 55 sash and extending inwardly from that edge of the sash which is covered by the frame when the window is closed.

The friction drag consists of a pair of friction shoes 6 connected at their outer ends 60 to the frame by a link 7 and yieldingly held against the wall of the recess by an intermediate spring device consisting for example of a pair of oppositely disposed laminated springs 8 connected at the center and 65 each having their ends bearing against the interior of one of the shoes to tightly press same against the wall of the recess, which latter is provided with a metallic lining 9. The friction shoes are preferably constituted by a tube split longitudinally at diametrically opposite points and the link 7 is pivotally connected thereto by means of a pin 10 which passes through the halves of 70 the split tube and through the link, segmental distance pieces 11 being located between the link and the halves of the tube 75 and surrounding the pin 10 on opposite sides of the link.

The outer end of the link 7 is pivotally 80 connected to the frame or other stationary member 4 through the medium of a plate 12 secured to and preferably countersunk in the edge of the frame at a point opposite recess 5 and presenting spaced lugs 13 between which the outer end of the link is disposed and pivotally connected thereto by 85 a pin 14, the recess being of a size to permit of the entrance of the lugs so that when the window is closed the recess is covered by 90 the frame and the friction drag protected from the elements.

The frictional resistance set up between the shoes 6 and the wall of the recess, by 95 springs 8, holds the window against accidental movement, but in swinging the window to a desired position the frictional resistance is overcome and the drag moved by the window to a different position where it again frictionally holds the window 100 against accidental movement, the drag being thus automatically adjusted to hold the window in the desired position.

A stop 15 at the mouth of recess 5 prevents excessive withdrawal of the drag and 105 it will be seen that by inclosing the latter, all unsightliness is avoided and no additional space is required, while the device is

protected from the elements as the recess is covered and the drag completely inclosed when the window is closed.

What I claim is as follows:

- 5 1. In combination, a frame, a window sash hinged to the frame and having a recess therein, shoes within the recess, a spring device pressing the shoes against the wall of the recess and a connection between the shoes and frame and having a lateral movement within the recess.
- 10 2. In combination, a frame, a window sash hinged to the frame and having a recess therein, the edge of the frame being adapted to cover the recess, a tube within the recess, such tube being longitudinally split at
- 15

diametrically opposite points, a pair of laminated springs between and respectively bearing against the halves of the tube, a stop to limit the withdrawal of the tube from the recess and a link pivotally connected at its ends to the tube and frame respectively and having a lateral movement within the recess.

In testimony whereof, I have signed my name to this specification in the presence of two subscribing witnesses.

CHARLES JEWETT SAXE.
